(57) **CLAIM**

We claim the ornamental design for a wireless animal training transmitter, as shown and described.

DESCRIPTION

FIG. 1 is a perspective view of a wireless animal training transmitter showing our new design;

FIG. 2 is a side view thereof;

FIG. 3 is a front view thereof;

FIG. 4 is an opposite side view thereof;

FIG. 5 is a rear, perspective view thereof;

FIG. 6 is a top view thereof; and,

FIG. 7 is a bottom view thereof.
